UNITED STATES PATENT OFFICE.

CLYDE ORMOND, OF RIRIE, IDAHO.

DISPENSING MEANS FOR SHAVING BRUSHES.

Application filed March 10, 1927. Serial No. 174,132.

This invention relates to a new and useful device in the nature of a shaving brush, such as used by men to lather the face prior to shaving. The invention relates particularly to a shaving brush adapted to hold the shaving cream and a means of forcing the shaving cream into the bristles of the shaving brush as may be desired.

The object of the invention is to provide a shaving brush of novel construction and arrangement of parts, hereinafter more fully described, claimed and illustrated in the accompanying drawing.

Fig. 1 is a side elevational view of my improved shaving brush.

Fig. 2 is a longitudinal central sectional view thereof.

Fig. 3 is a similar view to that shown in Fig. 2 illustrating a further development thereof.

Fig. 4 is an enlarged fragmentary central longitudinal sectional view illustrating a modification thereof.

As here embodied my improved shaving brush comprises bristles 10, such as commonly used for shaving brushes. The bristles 10, are attached to the holder 11, which may be of rubber, or the like. The bristles 10 being molded to the holder 11, and extended therefrom. The holder 11, is of ring shaped construction, and is attached to the spindle 13, being molded thereto. The spindle 12, is of hollow construction, provided with a cavity 13, and an opening 14, or aperture, intercommunicative with the cavity 13 and the central portion of the above mentioned bristles 10. The handle member 15, may be of any suitable contour, adapted to readily be held in the hand. The handle member 15, is of hollow construction, provided with the cavity 16. The cavity 16, has formed or cut therein threads 17, adapted to receive the threaded portion 18 of the above mentioned spindle 12.

The above described construction being such as will permit the cavity 16 of the holder member 15 to be filled with shaving cream, and which will permit the said shaving cream to be forced through the cavity 18, and through the opening 14, into the bristles 10, when the spindle 12 is screwed into the holder member 15.

In Fig. 3 of the accompanying drawing, I have shown the handle member 15, somewhat extended. The handle member 15, is provided with a second cavity 20, having

an annularly grooved recess 21 and an inwardly extended portion 22. The ejector member 23, is slidably mounted in the said second cavity 20, and is held in position 60 therein by the ring member 24, threadedly attached in the extremity of the holder member 15. The expansion spring 25 is positioned in the second cavity 20 and in the annularly grooved recess 21, so as to 65 normally hold the ejector member 23, at the rear of the holder member 15, as clearly shown in Fig. 3. The ejector member 23, is provided with an extended portion 26, adapted to normally extend slightly 70 through an axial aperture formed on the inwardly extended portion 22. The ejector member 23, is provided with an axial aperture 27, adapted to slidably receive the inner ejector member 28. The inner ejector member 28, is provided with an extended element 29, of somewhat smaller diameter, adapted to be extended slightly through an axial aperture formed in the ejector member 23. The expansion spring 30, is positioned in the axial aperture 27 of the ejector member 23, so as to normally hold the inner ejector member 28, at the rear of the ejector member 23. The pin 31, is secured to the inner ejector member 28, and is extended 75 therefrom, so as to engage in an elongated slot 32, formed in the ejector member 23.

The above described construction being such as will permit the extended element 26 of the ejector member 23 to be slidably engaged in the above mentioned cavity 13, and which will permit the extended element 29 of the inner ejector member 28, to be slidably engaged in the above mentioned opening 14, as a means of forcing the shaving cream in the cavity 13, and in the opening 14, into the bristles 10. The latter described construction being such as will permit the interior of my improved shaving brush to be kept or maintained in a clean 100 and sanitary condition.

It should be understood that when the cavity 13 and the cavity 16 are filled with soap the ejector 23 when forced inwardly will displace some of the soap through the passage 14. With the handle member 15 positioned as shown in Fig. 3, the ejector can force out only that amount of soap which it displaces and after it has been forced inwardly to the extent of its full length, the handle member 15 may be screwed downwardly on the spindle 12 for positioning the

ejector 23 closer to the spindle 12 to place the ejector in an operative position. Depression of the ejector 23 will again displace soap through the passage 14 until the ejector has been again extended completely into the cavity 16 and thereafter the ejector may be repositioned as above described.

In Fig. 4 of the accompanying drawing, I have shown ejector member 23 threadedly attached, as at 33, in the handle member 15. I have also shown the inner ejector member 28, threadedly attached, as at 34, in the ejector member 23. The ejector member 23, and the inner ejector member 28, are provided with apertures 35, and 36, respectively, adapted to receive a pin, or any convenient instrument or the like, as a means of engaging the latter mentioned elements in the cavity 13, and in the opening 14, for the purpose as hereinbefore set forth.

Having thus described my invention, what I claim as new and desire to protect by Letters Patent of the United States is as follows:

Dispensing means for shaving brushes comprising a tubular handle member having a compartment therein for retaining soap, a plunger slidably mounted in said handle member comprising a casing for displacing soap from said compartment, a forward hollow section adjustably screw threaded in said handle member having a discharge passage therein and adapted to be positioned relative to said handle member for permitting insertion of said casing thereinto for displacing soap therefrom, a rod slidably mounted in the casing of said plunger adapted to be extended into the discharge passage of said forward section when the latter is disposed within said tubular handle member for discharging soap therefrom, and a spring disposed in said casing engaging a shoulder on said rod for normally holding the same in retracted position in said casing and out of the soap retaining compartment.

In testimony whereof I affix my signature.

CLYDE ORMOND.
